SHEET METAL SLIP ROLL FORMER

William C. Tifft, Seymour, Conn., assignor to
Frederick Iron & Steel, Inc., Frederick, Md.

Application November 28, 1947, Serial No. 788,440

7 Claims. (Cl. 153—61)

1

This invention comprises novel and useful improvements in a sheet metal slip roll former and more specifically pertains to a device for rolling sheet metal into various conical or cylindrical shapes.

It is the primary object of this invention to provide an improved apparatus for coiling sheet metal into rolls of predetermined size and shape.

A further important object is to provide an apparatus in accordance with the foregoing object capable of easily accommodating itself to various thicknesses of sheet metal and of producing rolls of various selected sizes and shapes.

Yet another important intention is to provide a machine in conformity with the preceding objects, which is capable of easy and quick release and removal of the formed sheet metal roll therefrom.

A very important feature of the invention consists in providing a device having a tiltable pressure roll journaled in relatively fixed bearings, a movable pressure roll whose bearings are adjustable to vary its spacing from the tiltable pressure roll and a bending roll likewise journaled in bearings adjustable with respect to each of the other rolls.

A further important feature consists of forming one bearing of the tiltable pressure roll tilt-able and the other bearing easily releasable in order to tilt and free one end of the tiltable pressure roll to facilitate the removal of the material rolled thereabout.

Another important feature of the invention comprehends the provision of a camming lever for releasing the removable journal bearing and a tilting lever for swinging the tilting bearing of the tiltable pressure roll, these levers being positioned in juxtaposition for convenient manipulation by the operator.

Still another feature of the invention includes the provision of a novel and advantageous gearing assembly connecting the various rolls for timed operation thereof, together with a simple means for applying power to the rolls for rotating the same.

An additional feature comprises the provision of a gearing assembly for maintaining a constant and uninterrupted driving and synchronized engagement between the various rolls throughout their range of adjustment relative to each other.

And a final important feature to be specifically enumerated herein, resides in a novel construction of lever operated means for replacing and locking or releasing and removing the bearing cap of the removable bearing by successive

2

positions of the camming lever in a single or continuous movement thereof.

These, together with various ancillary objects and features of the invention which will later become apparent as the following description proceeds, are obtained by this device, a preferred embodiment of which has been illustrated by way of example only in the accompanying drawings, wherein:

10 Figure 1 is a perspective view of the machine from the front, in operative position;

Figure 2 is a fragmentary perspective view of the right end of the machine in its released position;

15 Figure 3 is a vertical transverse sectional view through the right end of the machine taken substantially upon the plane of line 3—3 of Figure 6, showing the operating mechanism therein, alternative positions and hidden portions of certain parts being shown in dotted lines;

20 Figure 4 is a fragmentary vertical longitudinal sectional view, taken substantially upon the plane of the section line 4—4 of Figure 5, of the left end of the machine;

25 Figure 5 is a vertical transverse sectional view through the left end of the machine, certain concealed parts thereof being indicated by dotted lines;

Figure 6 is a fragmentary elevational view of the right end of the device; and,

30 Figures 7 and 8 are perspective views from the front and rear respectively of the adjustable journal bearings of the rolls.

35 Referring now more particularly to the accompanying drawings, wherein like numerals designate similar parts throughout the various views, there is indicated at 10 in Figure 1 the bed plate, base or supporting frame of a device constructed in accordance with the principles of this invention.

40 Mounted upon the base 10, in spaced positions thereon, are a pair of supports 12 and 14 comprising the end supports for journaling and retaining a plurality of rolls as set forth hereinafter.

45 The end support 12 which may be called the tail support of the device, is preferably in the form of a housing, having a removable end closure plate 16 for obtaining access to the part housed therein. The support 14 which may be called the end support of the device is preferably an open framework construction in order to give greater access to the end of the tiltable pressure roll as set forth hereinafter.

50 Rotatably journaled in the two supports, and each having its ends individually adjustable

therein, are a pair of pressure rolls 18 and 20, the former being tiltable about its end journaled in the housing 12, while the latter is displaceable toward and from the tiltable roll 18, and is termed hereinafter the movable pressure roll; while a 5 third roll 22, shown best in Figures 3 and 5, has its extremities journaled in the two supports 12 and 14 for independent movement thereof.

Attention is directed first to the means for journaling and adjusting the movable pressure 10 roll 20, and for this purpose reference is made more particularly to Figures 3 and 4. As shown, the extremities of the movable roll 20, are provided with bearing portions 24 of reduced diameter, it being understood that these bearing portions could be provided at any other part of the roll besides or in place of their position at the extremities. The reduced portions are journaled in bearing blocks 26, whose construction is shown best in Figures 7 and 8. The bearing blocks 26 are provided with bores 28 constituting journal bearings for receiving the reduced ends 24 of the roll 20, and are provided with parallel oppositely positioned guide surfaces 30 having laterally extending guide flanges 32 formed at the ends thereof. The guide surfaces 30 and flanges 32 are slidably received in and guided in complementary-shaped guide channels 34 which are vertically disposed in alignment with each other in the two supports 12 and 14. A vertical bore 36 opens to the lower part of the guiding channel 34, and is intersected by a similar horizontally disposed bore 38 opening from the front and exterior of the two end supports. The lower ends of the vertical bores 36, as shown best in Figure 3, and Figure 5, are closed by a plug 40, which also serves as a stop to limit the downward movement of a push rod 42 which is slidable in the bore 36 and whose lower extremity is wedge-shaped to provide a cammed surface or bevel 44 at the lower end thereof. This bevelled surface is positioned to face and be contacted by and operated by a similar bevelled surface 46 formed at the inner extremity of a second push rod 48 which is slidable in the bore 38.

It will thus be seen that the two bevelled surfaces 44 and 46 will serve to prevent relative rotation of the two engaging push rods 42 and 48, and will serve as cam operating means whereby movement of one rod longitudinally of its bore will produce a corresponding reciprocation of the other push rod. The outer end of the rod 48 is engaged by the inner end of a screw-threaded stem 50 engageable in corresponding screw threads in the bore 38, this stem being provided with an operating knob or handle 52 for rotating the same.

It will thus be readily seen that the knob 52 of either of the two end supports may be rotated to thereby cause a vertical adjustment of the bearing blocks supporting the end of the movable or lower pressure roll, whereby the latter may be moved toward and from the upper pressure roll, and whereby the axis of rotation of the movable roll may be inclined slightly with respect to the horizontal plane and with respect to the axis of the upper roll.

The most important function of this adjustment however, is to vary the clearance between the upper and lower pressure rolls in order to adapt the same to accommodate different thicknesses of sheet metal plates adapted to be rolled or formed thereby.

Attention is next directed to the third or the bending roll indicated at 22, and the means for

adjusting the position of the same. This roll is formed similarly to the two pressure rolls 18 and 20, and at its extremities is provided with bearing blocks 26 which are identical with those described in connection with the movable pressure roll 20. These bearing blocks are slidably received in a guide channel or bore 54 which is formed in an angular extension 56 formed upon the rear surfaces of the two supports 12 and 14. As shown in Figure 3, the upper end of the bore 54 is open, as the guide is applied to the support 14, while as shown in Figure 5, this bore opens into the interior of the housing of the support 12. In both supports however, the guide bores 54 are parallel to each other and have their longitudinal axes inclined with respect to the vertical plane passing through the axes of the two pressure rolls, and are so positioned and so proportioned as to place the upper surface of the bending roll 22 always above the horizontal plane passing between the two pressure rolls, whereby a sheet or plate of metal when passed between the two pressure rolls will engage the surface of the bending roll, and be bent or curled upwardly thereby.

Screw-threadedly engaged within the extension 56 is the shank 58 whose inner end engages the lower surface of the bearing block 26, and whose outer end is provided with an operating knob 60. Obviously, upon rotation of the knob 60, the bearing blocks 26 may be adjusted toward and from, and vertically with respect to the horizontal plane passing between the two pressure rolls. By individually adjusting the knobs 60, the axis of the bending roll 22 may be disposed parallel to or inclined at various angles with respect to the axes of the two pressure rolls, whereby a sheet passing therebetween may be rolled in a cylindrical form upon a variable and adjustable radius, or may be rolled in a conical form with a variable degree of concavity.

Attention is now directed chiefly to Figures 4 and 5 for a description of the means for pivotally and tiltably mounting the upper roll 18. One end of this roll is journaled in bearings formed in the forked or bifurcated arms 62 and 64 of a bracket 66 which is oscillatively and pivotally mounted upon a fulcrum pin 68 carried by internal lugs or shoulders 70 formed in the tail support 12. The fulcrum pin 68 is disposed transverse to the longitudinal axis of the roll 18, whereby the latter may be tilted in the vertical plane, about the fulcrum pin 68. To lock the bearing bracket 66 and the tiltable roll 18 against this tilting movement, and in some instances to assist in effecting such movement, an arm 72 is secured as at 74 to the vertical end face of the bearing block 66, is provided with an offset portion 76 which is receivable within the confines of the opening 78 closed by the closure plate 16, and which terminates at its lower end in an apertured portion 80 which is disposed through an opening 82 in the bottom of the tail support 12 and into a hollow chamber 84 extending lengthwise of the base member 10. The offset portion 76 provides clearance for certain other mechanism housed within the tail support 12 as set forth hereinafter, during oscillation of the arm 72. A connecting rod 86 has one end screw-threaded as at 88 and this screw-threaded end is loosely received within the apertured end 89 of the operating arm 72, while a pair of lock nuts 90 are secured upon the screw-threaded end 88 for the purpose of adjusting the connecting rod or link 86 with respect to the end of the arm 72.

for oscillating the latter upon reciprocation of the connecting link. The connecting link 86 extends the substantial length of the chamber 84 within the bed 10, and at its forward end is provided with a down-turned portion 92 which is pivotally engaged with a locking lever 94 extending within the chamber 84, and whose rear end is pivotally connected as at 96 to the bed 10, while the front end extends through a slot 98 in the front wall of the bed 10.

As shown best in Figure 2, this slot 98 is provided with a depressed portion 100 by means of which the lever 94 may be depressed at one end of its stroke and locked or retained in this position. This locked position corresponds to the up-tilted or raised position of the tiltable pressure roll 18, and thus serves to maintain the latter in proper position for releasing or removing a sheet which has been rolled or formed by passage through the roll.

As shown more clearly in Figures 2 and 3, the other end of the tiltable roll 18 is provided with a reduced bearing portion 102 which rests within the lower half of a bearing 104 formed in the upper surface of the head support 14. A removable bearing cap 106, is provided with a complementary bearing surface 108 which rests upon the upper surface of the bearing 102 for releasably retaining the latter in the head support as set forth hereinafter. This bearing cap 106 is provided with bifurcated ears or lugs 110, see Figure 6, by means of which the bearing cap is pivoted on a pivot pin 112 carried by a pair of parallel upstanding lugs 114 constituting bifurcated extensions rising from the head support 14. The bearing cap 106 thus straddles and is pivotally mounted upon the bifurcations 114, while a camming lever 116 is pivotally mounted between the bifurcations 114, by means of a pivot pin 118. As will be seen from Figure 3, the pivot pin 118 is mounted downwardly and inwardly of the head support with respect to the pivot pin 112 which journals the bearing cap. The upper end of the lever 116 is provided with screw threads 120, upon which is adjustably secured an operating handle 122, whose lower end is contoured to provide a cam surface 124. The pivot end of the bearing 106 is longitudinally notched or cut away as at 126, to provide the above-mentioned bifurcations 110, and to further provide a slot 128, for receiving the lever 116. Above the slot 128, a bifurcated portion of the bearing cap 106 is recessed as at 130 the floor of this recess constituting a cam surface engageable by the lower end of the cam portion 124 of the handle 122, for locking the bearing cap 106 in its closed position upon the journal 102, as illustrated in full line in Figure 3. Adjacent this camming surface 130 is a depression 132 which receives the cam 124 upon the initial part of the opening movement of the latter, to thus release the closing pressure upon the bearing cap 106. At its other end, the recess 130 is provided with a shoulder 134 which is engageable by the operating lever 116, whereby the latter will lift and pivot the bearing cap from the dotted line open position of Figure 3 into its closing or full line position shown in Figure 3.

From this description, the operation of the camming lever and the bearing cap will be readily understood. With the parts in the closed and locked position of Figure 3, the handle 122 is first drawn rearwardly a sufficient distance to cause the cam surfaces 124 and 130 to disengage, and whereby the cam 124 drops into the depre-

sion 132. This releases the locking pressure on the bearing cam 106 and permits a slight counter-clockwise pivoting of the bearing cap about its fulcrum 112, whereby the bearing 108 will be disengaged from the shaft bearing 102 of the roll 18. When now continued opening movement of handle 122 causes the cam 124 to engage the outer or rear wall of the depression 132, further counter-clockwise movement of the handle causes the cam portion 124 of handle 122 to bear against the rear wall of the depression 132, and thereby cause counter-clockwise rotation of bearing cap 106 about in fulcrum 112, until the fully open position indicated in dotted lines in Figure 3 is reached. At this point, or slightly prior thereto, the eccentricities of the fulcrum pins 112 and 118, will permit complete disengagement of the lever 116 from the end of the slots 126 and 128, thereby permitting rotation of handle 122 upon the screw-threaded portion 120, in order to regulate the desired tightness of the bearing engagement of the surfaces 104 and 108 upon the bearing 102.

With the parts in the open position shown in Figure 3, the end of the upper pressure roll 18 may be lifted, or tilted in a vertical plane, and this movement may be assisted by manipulation of the lever 94 as above mentioned. In any event, the roll may be tilted and retained in its elevated position by engaging the lever 94 in the locking recess 100 of the slot 98, thus permitting the operator of the machine to open the pressure rolls and readily withdraw a slip which has been formed thereby.

Attention is now directed more specifically to the gearing assembly for operating and driving the rolls. As will be seen by reference to Figures 4 and 5, all of the gearing is housed within the casing of the tail support 12, thus rotating the gearing at the point of the least relative movement between the rolls. As will be seen by reference to Figures 4 and 5, the roll 18 has rigidly attached thereto a gear 136 journaled between the bifurcations 62 and 64 of the bracket 66, which gear is constantly in mesh with an idler gear 138 journaled on a lug or extension 140 carried by the bracket 66. The idler 138 is constantly engaged with a similar idler 142 journaled on a pin mounted in the housing of the tail support 12, which second idler is also inmeshed with the gear 144 rigidly mounted on the end of the movable pressure roll 20. It will thus be seen that the two pressure rolls 18 and 20 are geared to each other to revolve in opposite directions. The bender roll 22 is provided with a driving gear 146 which meshes with an idler 148 journaled at the end of a strap or leaf 150 whose other end is pivoted upon the end of the bender roll adjacent the gear 146. A second connecting link 152 has its extremities journaled respectively on the shaft carrying the idler gear 148, and the end of the lower or movable pressure roll 20 adjacent the gear 144.

The opposite end of the movable pressure roll 20 is extended through the head support 14, and is provided with a squared portion 154 which may be engaged by a crank 156 or any other means such as a power source for operating and rotating the lower pressure roll. As shown best in Figure 2, the extending portion of the lower pressure roll 20 rides in a vertical slot 158 which thereby permits the vertical adjustment of the lower pressure roll as set forth hereinbefore. It will thus be understood that upon rotation of the extremity 154, by either manual or power means,

the lower pressure roll is rotated; and through the gearing gear teeth 144, 142, 138 and 136 causes rotation in the reverse direction of the upper or tiltable pressure roll. When these pressure rolls are set to the proper adjustment, the sheet or plate of material is squeezed between these rolls and forced therethrough by the oppositely rotating surfaces thereof. At the same time, the gear 144 of the lower or movable pressure roll 28 by means of the gearing 148 and 146, causes rotation of the bender roll 22 in the same direction as that of the lower power roll. It should be here noted that the slight relative movement of the gear 138 with respect to the gear 142 occasioned by the tilting or pivoting of the bracket 66 upon its fulcrum 68, is compensated for by the center line of pin 68 about which rotation of bracket 66 takes place being in alignment with the rear edge of the gearing train so that such rotation tends to separate the pitch lines of gears 138 to 142 and allows for clearance in the tilted position of roll 18 and pitch line operation in the working position of roll 18. Similarly, the vertical displacement of the lower pressure roll 28 and the gear 144 is permitted by the clearance between the teeth of gears 144 and 142. It should be here noted that this relative movement is comparatively small the relatively greater movement of the bender roll in its adjusted position with respect to the two pressure rolls, is obtained within altering the gearing drive thereof, by means of the linkage arrangement 150 and 152 and the idler gear 148 thereby.

It should be here noted that the principles of the invention are not limited to the embodiment as described above. Thus, instead of a bender roll, there may be provided any other means for imparting a bend to sheet metal slips fed through the pressure rolls; while obviously one of the pressure rolls may be maintained stationary, and the tilting end adjusting effects obtained from the other roll.

Since numerous modifications will readily occur to those skilled in the art after a consideration of the foregoing specification and accompanying drawings, it is not intended to limit the invention to the exact construction shown and described except as required by the appended claims.

Having described the invention, what is claimed as new is:

1. A sheet metal slip roll former including a base having an elongated chamber, spaced supports thereon including a hollow support, a pair of pressure rolls journaled in said supports including a tiltable roll, a bracket in said hollow support journaling said tiltable roll and pivoted upon an axis transverse the roll, tilting means in said hollow support secured to said bracket and extending exteriorly of said hollow support and into said chamber an elongated slot in the wall of said base communicating with said chamber, a lever pivoted to said base and tilting means and slidable in said slot.

2. A sheet metal slip roll former including a base having an elongated chamber, spaced supports thereon including a hollow support, a pair of pressure rolls journaled in said supports including a tiltable roll, a bracket in said hollow support journaling said tiltable roll and pivoted upon an axis transverse the roll, tilting means in said hollow support secured to said bracket and extending exteriorly of said hollow support and into said chamber an elongated slot in the wall of said base communicating with said chamber.

5

ber, a lever pivoted to said base and tilting means and slidable in said slot, a laterally recessed portion in the wall of said elongated slot, said lever being engageable in said recessed portion to secure the tiltable roll in tilted position.

3. A sheet metal roll former including a base, spaced supports thereon, upper and lower pressure rolls mounted in said supports, said upper roll being pivotally journaled in one support for vertical tilting movement, the other support having a journal bearing in its upper surface to receive the end of the upper roll, a bearing cap pivoted to said support at one side of the journal bearing and having a journal bearing in its lower surface for receiving the end of the upper roll, a locking lever pivoted to said support on the same side of the support as the bearing cap and below and to one side of the cap pivot, a longitudinal slot in said cap for slidably receiving said lever, cooperating cam surfaces on the upper surface of said cap and on said lever for locking said cap upon said support in engagement with the upper roll.

4. The combination of claim 3 wherein said bearing cap slot is open at the pivoted end thereof for endwise passage of said lever.

5. A sheet metal roll former including a base, spaced supports thereon, upper and lower pressure rolls mounted in said supports, said upper roll being pivotally journaled in one support for vertical tilting movement, the other support having a journal bearing in its upper surface to receive the end of the upper roll, a bearing cap pivoted to said support and having a journal bearing in its lower surface for receiving the end of the upper roll, a locking lever pivoted to said support, a longitudinal slot in said cap for slidably receiving said lever, cooperating cam surfaces on the upper surface of said cap and on said lever for locking said cap upon said support in engagement with the upper roll, said lever having a screw-threaded shank and a handle adjustable thereon, the cam surfaces of the lever being carried by the handle whereby the cam surfaces may be adjusted relative to each other by rotation of the handle on the shank.

6. A sheet metal roll former including a base, spaced supports thereon, upper and lower pressure rolls mounted in said supports, said upper roll being pivotally journaled in one support for vertical tilting movement, the other support having a journal bearing in its upper surface to receive the end of the upper roll, a bearing cap pivoted to said support and having a journal bearing in its lower surface for receiving the end of the upper roll, a locking lever pivoted to said support, a longitudinal slot in said cap for slidably receiving said lever, cooperating cam surfaces on the upper surface of said cap and on said lever for locking said cap upon said support in engagement with the upper roll, said cap having its pivot disposed upwardly and outwardly of the lever pivot with respect to the axis of the support journal bearing, said bearing cap having a shoulder at one end of the slot and a depressed portion at the other end of said slot, said lever being movable selectively in the slot to engage the shoulder and the depressed portion to close and open the cap.

7. A sheet metal roll former including a base, spaced supports thereon, upper and lower pressure rolls mounted in said supports, said upper roll being pivotally journaled in one support for vertical tilting movement, the other support hav-

ing a journal bearing in its upper surface to receive the end of the upper roll, a bearing cap pivoted to said support and having a journal bearing in its lower surface for receiving the end of the upper roll, a locking lever pivoted to said support, a longitudinal slot in said cap for slidably receiving said lever, cooperating cam surfaces on the upper surface of said cap and on said lever for locking said cap upon said support in engagement with the upper roll, said cap having its 10 pivot disposed upwardly and outwardly of the lever pivot with respect to the axis of the support journal bearing, said bearing cap having a shoulder at one end of the slot and a depressed portion at the other end of said slot, said lever being movable selectively in the slot to engage the shoulder and the depressed portion to close and open the cap, said lever having a screw-threaded shank and a handle adjustable thereon, the cam surfaces of the lever being carried by the handle 20 whereby the cam surfaces may be adjusted relative to each other by rotation of the handle on the shank.
